SANITARY GARBAGE CAN COVER

Harry Meyer, New York, N. Y.

Application May 26, 1947, Serial No. 750,491

3 Claims. (Cl. 220—56)

1

This invention relates to a sanitary garbage can cover arrangement.

The main object of my invention is to provide a cover for a garbage can which will retain the garbage in said can and prevent the garbage from being scattered upon the streets when the cover of the can is in closed position, thereby safeguarding the health of the surrounding neighborhood, inasmuch as the scattering of such garbage upon the streets is positively prevented due to the cover locked upon said garbage can.

It is an object of the present invention to provide an arrangement for locking a garbage can cover to the can in such a manner that the same cannot be lifted from the same by dogs or other animals within the neighborhood and such that the mechanism is of simple construction and easily operated to effect a locking of the cover or a release of the cover from the can.

For other objects and for a better understanding of the invention, reference may be had to the following detailed description taken in connection with the accompanying drawing, in which

Fig. 1 is a fragmentary perspective view of a garbage can containing the cover inventions therewith.

Fig. 2 is a cross-sectional view taken on line 2—2 of Fig. 1.

Fig. 3 is a cross-sectional view taken on line 3—3 of Fig. 2.

Fig. 4 is a view similar to Fig. 3, the handle having been moved into another position.

Fig. 5 is a front elevational view of the clamp assembly.

Fig. 6 is a cross-sectional view taken on line 6—6 of Fig. 3.

Referring now to the figures, 10 represents a garbage can which has a top flange 11. A cover 12 is adapted to be fitted over the top flange 11 to close the can. A handle 13 is provided for effecting the lifting of the cover 12 from the can and for replacing it on the same.

The cover 12 is provided with internal projections 14 located one hundred and twenty degrees apart and adapted to be seated beneath the flange 11. At the opposite side of the cover 12 is a slot 15 through which can be extended a block 16 for engagement with the face of the can. This block is mounted on a resilient strap 17 which is riveted at 18 to the cover and is biased to a disengaged position as shown in Fig. 4.

Extending over the strap 17 and the slot 15 is a guide plate 19 of which the strap 17 may form an integral part thereof as shown more clearly in

2

Fig. 5. The plate 19 will be riveted by the rivets 18 and 21. The guide plate 19 has turned in guide portions 22 for retaining and receiving an operating plate 23 having a handle 24 thereon. As the handle shifts the plate 23 along the guide portions 22, the strap 17 will either be depressed to cause the engagement of the block 16 with the can or will be released to permit the removal of the cover from the can.

10 Upon the block 16 being released, the cover can be lifted by the handle 24 or by the handle 13 from the top of the can. To replace the cover on the can, the projections 14 at the opposite side of the cover from the handle 24 are first fitted under 15 the flange 11 and then the front side of the cover is dropped down into place. Thereafter the handle 24 will be slid along the guide member 19 and the block 16 pressed against the side of the can.

While various changes may be made in the detail construction, it shall be understood that such changes shall be within the spirit and scope of the present invention as defined by the appended claims.

Having thus set forth and disclosed the nature 25 of this invention, what is claimed is:

1. A can cover locking device including a cover having a depending skirt portion adapted to telescope with the can, projections provided on the cover skirt portion adapted to be seated beneath 30 a flange on the can, said cover skirt portion having a side opening, a block adapted to be extended through the opening for engagement with the side of the can, biasing means tending to move the block to an out-of-engagement position, a member 35 slidable over the biasing means and block for causing the inward movement of the block into engagement with the can, and means for securing the movable member to the can cover for movement over the biasing means and the block.
- 40 2. A can cover locking arrangement comprising a cover having a depending skirt portion adapted to telescope with the can, projection means on the cover skirt portion adapted to be extended over a flange on the top of a can as the cover is fitted thereon, said cover skirt portion having a side opening at a location on the cover opposite to the projection means, a block adapted to be extended through the opening for locking engagement with the can face, a resilient strap 45 connected to the block and adapted to normally withdraw the block from the opening, guide portions secured to the cover over the strap and over the opening, a plate slidable through the guide portions to force the block through the opening and into engagement with the can or to release

the strap and block, said plate having a handle portion thereon.

3. A can cover locking arrangement for securing a can cover to the top of a can comprising a cover having a depending skirt portion adapted to telescope with the can, projections secured to the cover skirt portion and adapted to fit over and beneath a flange on the can, said can cover skirt portion having an opening in the side of the frame, a block adapted to be extended through 10 the opening for engagement with the can, a guide member having guide portions fixed to the can cover over the opening, said guide member having a struck out resilient portion, said block fixed to the end of the struck out portion, and a plate 15

slidable through the guide member to cause the struck out portion and the block to be moved inwardly so that the block will engage with the can, said plate having a handle portion extending upwardly from the top of the cover.
